(57) **CLAIM**

An ornamental design for a removable water resistant pouch for attaching to waders, as shown and described.

DESCRIPTION

FIG. 1 is a perspective view of a removable water resistant pouch for attaching to waders;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof;

FIG. 8 is a back side view of the removable water resistant pouch for attaching to waders, attached to waders; and,

FIG. 9 is a front side view of the removable water resistant pouch for attaching to waders, attached to waders.

It should be understood that the labels used herein for describing orientation (e.g., front, back, top, bottom, right, and left) are merely for reference, and the design may be disposed in any manner and still be within the scope of the present disclosure.

The broken line showing of the waders in FIGS. 8-9 is included for the purpose of illustrating the environment of the claimed design and forms no part thereof.
